VARIABLE FLUSHING CONTROL FOR TOILETS

Harlan J. Christie, South San Gabriel, and
Michael J. Corcoran, Arcadia, Calif.

Application September 21, 1954, Serial No. 457,410

4 Claims. (Cl. 4—57)

This invention relates to a variable flushing control for 15 toilets.

It is an object of our invention to provide a new and improved type of flushing control for toilets in which the toilet can either be flushed in the normal manner to remove solids or flushed for any desired shorter period of time to remove liquids, primarily for the purpose of saving water.

It is particularly an object of our invention to provide such a device which does not interfere in any way with the normal flushing of the toilet and which also permits the user to select any desired shorter period of time for the flushing operation. Such shorter period of time is not pre-set, but is entirely within the control and discretion of the user.

Another object of our invention is to provide a new and improved type of flushing control for toilets. A related object of our invention is to provide a variable flushing control of the class described which is simple in construction, economical to manufacture and simple to install, so that it is capable of being sold and used on a widespread scale.

A further object of our invention is to provide a variable flushing control for toilets which will save a considerable amount of water, thus being of benefit both to the user and to the public.

Our invention also comprises such other objects, advantages and capabilities as will later more fully appear and which are inherently possessed by our invention.

While we have shown in the accompanying drawings a preferred embodiment of our invention, it should be understood that the same is susceptible of modification and change without departing from the spirit of our invention.

Referring to the drawing, the figure is a front elevational view of my device in use in a toilet tank, with the upward movement of the upper portion of the tube and ball valve shown in dotted lines and with parts of the ball valve, aligning bracket and tube broken away.

A preferred embodiment which has been selected to illustrate our invention comprises a toilet tank construction having a vertically disposed overflow tube 10 of the conventional type now in use. Extending around tube 10 adjacent its midportion and attached thereto is a collar 11 which surrounds tube 10 and has a projection 12 which extends horizontally from one side of tube 10. An adjustable aligning bracket having a hollow cylindrical portion 13 and an arm 14 is mounted so that arm 14 is pivotally and adjustably attached to the end of projection 12 by means of a wing nut 15 which is loosened and retightened to adjust cylindrical portion 14 to its proper position.

A small hollow tube 16 is loosely slidably mounted in hollow cylindrical portion 13 and is adapted to move in a vertically reciprocal manner with its direction of movement being controlled by the positioning of cylindrical portion 13.

The bottom of tube 16 is screw threadedly mounted in

2

the top of a ball valve 17 so that tube 16 forms a passage leading into the hollow interior of ball valve 17. The bottom of ball valve 17 is provided with a substantial opening 18 through which water can flow into or out of the interior of ball valve 17.

Mounted in the top of tube 16 by screw threading or other suitable means is an air valve 19, which may be of a conventional type used in automobile tires. Air valve 19 is provided with an upwardly extending depressible valve stem 20. When valve stem 20 is depressed, air is free to pass through valve 19 into or out of tube 16. Valve 19 is normally maintained in closed position by internally contained spring tension means.

Mounted adjacent the top of overflow tube 10 is a wide flat contact bar 21, one end of which surrounds tube 10 and is fixedly mounted thereon, while its opposite end is free from attachment and extends above the top of tube 16.

A conventional trip lever arm 22 is disposed above the top of overflow tube 10 and is operated by a trip lever control 22a which acts to move the free end of lever arm 22 upwardly to flush the toilet.

A lift wire 23 is attached at its top end adjacent the free end of trip lever arm 22 and extends downwardly to 25 form a slip link 24 at its opposite end which extends around tube 16. A circular stop member 25 extends around tube 16 above slip link 24 and is sufficiently large in diameter to prevent slip link 24 from passing over it.

The bottom portion of ball valve 17 is removably disposed in a seat 26 of corresponding contour. The cylindrical portion 13 of the adjustable aligning bracket is aligned to such a position that tube 16 acts to guide ball valve 17 downwardly into seat 26 after the toilet has been flushed.

In operation, trip lever control 22a is moved to operative position, causing the free end of trip lever arm 22 to move upwardly to start the toilet flushing operation. The upward movement of the free end of trip lever arm 22 causes lift wire 23 to move upwardly, imparting upward movement to slip link 24, which engages stop member 25 and carries tube 16 upwardly. This lifts ball valve 17 from seat 26.

Water flows from the tank out through seat 26 to flush the bowl. If toilet trip lever 22a is not maintained in operative position, the free end of trip lever arm 22 immediately moves downwardly to its normal position. The ball valve 17 moves downwardly with the falling water level in the tank, its path being guided by tube 16 and cylindrical member 13. Ball valve 17 resumes its place in seat 26 as the tank is fully drained, sealing the water outlet to permit the tank to refill. This is a normal flushing operation, which is substantially unaffected by our variable flushing control.

In order for our variable flushing control to function, 55 the user need only hold trip lever control 22a in operative position, causing the free end of trip lever arm 22 to remain in upward position. This maintains valve stem 20 in engagement with contact bar 21 while a substantial amount of air passes out of tube 16, such air being replaced by air from the interior of ball valve 17, which air is in turn replaced by water which enters the interior of ball valve 17 through opening 18.

When trip lever control 22a is released, ball valve 17 is much heavier than normal due to the water which it 60 contains. It therefore moves rapidly to the bottom of the tank to seal seat 26 and stop the flushing operation before all of the water has passed from the tank.

The water which is contained in ball valve 17 is discharged through opening 18 after ball valve 17 is in 65 position on seat 26. Such water passes into the bowl and is replaced by air to restore ball valve 17 and tube 16 to their previous condition.

The trip lever control 22a may be held in operative position any desired length of time selected by the user to provide any desired timing and amount of flushing of the toilet.

The top edge of the tube 16 may, if necessary, be provided with a small notch or slot adjacent the valve stem 20 to prevent the top of tube 16 from forming an air tight seal with the bottom of contact bar 21. Such a seal would interfere with the flow of air out of tube 16. The smallest type of neck or opening through which air could pass would be sufficient for this purpose.

We claim:

1. In a variable flushing control for toilets, a hollow tube vertically reciprocally mounted within a flush tank, a ball valve attached to the bottom of said tube, said ball valve having a hollow interior connected to the hollow interior of said tube, said ball valve having a substantial opening in the bottom thereof adapted to permit water to flow into and out of said hollow interior, an air valve mounted adjacent the top of said tube, said valve having a depressible valve stem extending upwardly from the top of said tube, said valve normally preventing air from leaving said tube, said valve permitting air to leave said tube only during the time when said valve stem is depressed, a contact bar disposed within said tank above said valve stem, a trip lever having an operative position and a non-operative position, means normally maintaining said trip lever in non-operative position, connecting means extending between said trip lever and said tube whereby said tube is moved upwardly and said ball valve unseated by movement of said trip lever to operative position, said valve stem being depressed by contact with said contact bar as long as said trip is held in operative position, said valve stem returning to closed position when said trip lever is released to non-operative position, said ball valve being reseated substantially immediately after said trip lever has been held in operative position and released, due to the weight of water entering said ball valve to replace air passing out of said tube, said trip lever thus determining the length of time the toilet is flushed.

2. The subject matter of claim 1, said trip lever being connected to a toilet flushing control external to said tank and being manually operable by the user to flush the toilet for any period of time selected by the user.

3. In a variable flushing control for toilets, a hollow tube vertically reciprocally mounted within a flush tank, a ball valve attached to the bottom of said tube, said ball valve having a hollow interior connected to the

hollow interior of said tube, said ball valve having a substantial opening in the bottom thereof adapted to permit water to flow into and out of said hollow interior, an air valve mounted adjacent the top of said tube, said valve having a depressible valve stem extending upwardly from the top of said tube, said valve normally preventing air from leaving said tube, said valve permitting air to leave said tube only during the time when said valve stem is depressed, contact means disposed within said tank above said valve stem, a trip lever disposed within said tank, connecting means extending between said trip lever and said tube whereby said tube is moved upwardly and said ball valve unseated by operation of said trip lever, said valve stem being depressed by contact with said contact means as long as said trip lever is held in operating position, said valve stem returning to closed position when said trip lever is released, said ball valve being reseated substantially immediately upon release of said trip lever due to the weight of water entering said ball valve to replace air passing out of said tube, said trip lever thus determining the length of time the toilet is flushed.

4. In a variable flushing control for toilets having a ball valve with a hollow interior, an air valve connected to said hollow interior, a depressible valve stem extending upwardly from said air valve, said valve normally preventing air from leaving said ball valve, said air valve permitting air to leave said ball valve only during the time when said valve stem is depressed, contact means disposed above said valve stem, connecting means extending between the toilet flushing control and said ball valve whereby said ball valve is unseated by operation of said flushing control, said valve stem being depressed by contact with said contact means to permit water to enter the hollow interior of said ball valve during continued operation of said flushing control, said ball valve being reseated substantially immediately upon release of said flushing control due to the weight of water therein, said flushing control thus determining the length of time the toilet is flushed.
